Primary Examiner — Joseph Kukella*Assistant Examiner* — Heather Wencl(74) Attorney, Agent, or Firm — Donald Debelak(57) CLAIM

The ornamental design for a sand garden set, as shown and described.

DESCRIPTION

FIG. 1 is a perspective view of the sand garden set, showing the new design;

FIG. 2 is a right side elevation view thereof;

FIG. 3 is a left side elevation view thereof;

FIG. 4 is a front view thereof;

FIG. 5 is a rear view thereof;

FIG. 6 is a top plan view thereof; and,

FIG. 7 is a bottom plan view thereof.

The broken lines in the drawings depict portions of the sand garden set that form no part of the claimed design.

1 Claim, 6 Drawing Sheets
